Primary Examiner — Ian Simmons*Assistant Examiner* — Charles Hanson(74) *Attorney, Agent, or Firm* — Thorpe North & Western LLP(57) **CLAIM**

The ornamental design for the modular chair, as shown and described.

DESCRIPTION

FIG. 1 is an elevated, perspective view of the modular chair in accordance with our invention;

FIG. 2 is a left side elevation view thereof;

FIG. 3 is a right side elevation view thereof;

FIG. 4 is a front end elevation view thereof;

FIG. 5 is a back end elevation view thereof;

FIG. 6 is a top plan view thereof; and,

FIG. 7 is a bottom plan view thereof.

The broken line showing of the holes on the back and seat is included for the purpose of illustrating environment and forms no part of the claimed design.
